UNITED STATES PATENT OFFICE.

HIRAM DILLAWAY, OF SANDWICH, MASSACHUSETTS.

IMPROVED GLASS-PRESS.

Specification forming part of Letters Patent No. 57,296, dated August 21, 1866.

To all whom it may concern:

Be it known that I, HIRAM DILLAWAY, of Sandwich, in the county of Barnstable and State of Massachusetts, have invented new and useful Improvements in Glass-Presses; and I do hereby declare that the following is a full, clear, and exact description thereof, which will enable others skilled in the art to make and use the same, reference being had to the accompanying drawings, forming part of this specification.

The present invention consists, first, in a novel arrangement of parts for operating and moving the plunger or follower and obtaining the requisite degree of pressure upon the glass within the mold; second, in so arranging the mold that it can be moved into or out of the line of movement of the plunger or follower, the mechanism employed to accomplish which is susceptible of adjustment to accommodate the various sizes of molds; third, in so arranging the plunger or follower that when such portion of the same as is to cover the mold is over and upon it, it will be there tightly and firmly held while the plunger or follower is acting upon the inside of the mold—a result of great importance.

Having thus in general terms stated the principal features of the present invention, I will now proceed to describe the same in detail, together with other minor improvements involved in the press, reference being had to the accompanying plates of drawings, in which—

Figure 1, Plate 1, is an elevation of the rear side of a glass-press constructed according to my invention; Fig. 2, Plate 1, an elevation of one side of the same; Fig. 3, Plate 2, a vertical section taken in the plane of the line $x x$, Fig. 1, Plate 1; Fig. 4, Plate 2, a horizontal section taken in the plane of the line $y y$, Fig. 1, Plate 1; and Fig. 5, Plate 3, a horizontal section taken in the plane of the line $z z$, Fig. 1, Plate 1.

Similar letters of reference indicate like parts.

A in the drawings represents the table or bed-plate of the press, which, at each corner, is supported or rests upon the upper ends of posts B, that, at their lower ends, are connected together and braced by horizontal bars C, and also set or mounted on wheels or rollers

D, for convenience in moving the press about from place to place.

To the upper side of the table are fixed two parallel upright posts or rods, E E, that are connected together by a cross bar or head, F, near their upper ends, G, a vertical screw spindle or shaft passing loosely through the center of the fixed cross-head F, and also through cross-heads H and I, one above and the other below the fixed cross-head F, arranged to move up and down upon the uprights E E, hereinbefore referred to.

The upper cross-head, H, is confined or held on the spindle G between two screw-nuts, J J, one above and the other below the cross-head, by means of which the position of the said cross-head upon the spindle can be adjusted at pleasure.

The lower cross-head, I, rests upon the projecting flange K of the spindle, to which flange it is secured by bolting, riveting, or in any other proper manner.

The lower end, L, of the spindle G forms the plunger or follower for the mold, and is to be made of such shape as may be necessary for the mold used.

M is a horizontal head-plate on spindle G, which is held between two screw-nuts, N N, one above and the other below it. From each of the four corners of this plate M parallel vertical rods o extend, which rods are of equal length, two upon each side of the cross-heads, with the upper ends of those rods upon the same side of the cross-heads secured together by cross-bars P.

The outer ends of each of the cross-bars P are connected, through vertical rods Q, with the cross head or plate R, placed below the cross-head I, which plate R is set over the plunger end of the spindle G, and plays upon the fixed uprights of the bed-plate.

Between the head-plate R and the cross-bars P on the rods Q spiral springs R² are placed, on which springs the cross-bars rest, they being held upon the said rods by means of screw-nuts S.

To each end of the upper vertical sliding cross-head, H, similar connecting-rods T T are hung, that, extending downward upon each side of the press, are hung at their lower curved ends, U U, to one end of crank-arms V V of a common horizontal shaft, W, hung in vertical

elongated or slotted bearings W of parallel standards X , secured to the under side of bed-plate A at their upper ends, and at their lower ends to a common horizontal connecting-bar or brace, S . On each of the outer ends of the bar or brace S is hung a similar bent arm or rod, Z , that at their upper ends are hung to the opposite ends of the crank-arms V , hereinabove referred to, to that at which the connecting-rods T were hung.

To one end of the horizontal shaft W a vertical lever arm or handle, A^2 , is secured, by depressing or raising which, through the rods connecting said shaft W with the upper sliding cross-head, H , said cross-head, together with the screw-spindle on which it is placed and all the other parts connected therewith, as hereinbefore explained, are consequently lowered or raised, as the case may be, and thereby the plunger or follower of said spindle made to enter or to be withdrawn from the mold B^2 used, which is placed upon the upper side of the bed-plate A of the press in proper position therefor, this mold being arranged in a novel manner, as will be hereinafter described, so that it can be slid into position for the plunger to enter it, or out of line with the movement of the plunger, for the purpose of removing the article molded in it.

From the above description of the connecting parts between the operating-lever A^2 and the plunger or follower for the mold, and the manner in which they are arranged and combined, it is plain to be seen that when the cross head or plate R has been brought to bear upon the top of the mold, on which it comes to a rest or stop, by then continuing to depress the operating-lever the plunger can be made to still further enter the mold, passing through the said plate R , which, by such movement of the plunger, is firmly held, through the compression of the spiral springs R^2 , by the cross-arms P , moving upon the guide-rods O , thereby preventing all possibility of the cover or plate R rising from the mold as the plunger acts in it, the importance of which is obvious.

The mold B^2 is provided with a handle, A^4 , for convenience in removing it from the press. The mold is placed upon a plate, B^4 , that is arranged to slide upon a dovetail tenon or strip, C^4 , secured to the upper side of the table or bed-plate A . To the rear side of the sliding plate B^4 is hung the inner end of a short connecting-rod, D^4 , to the outer end of which is hung, by its swiveled nut E^4 , the lower end of a vertical inclined connecting-bar, F^4 , that is hung upon a fulcrum, G^4 , of the stationary projecting arm H^4 of the upper part of the press, and at its upper end is pivoted to one end of a short connecting arm or link, I^4 , arranged to slide in the horizontal groove J^4 of the upright K^4 of the press. To the other end of the link is hung a vertical connecting-rod,

L^4 , in the lower end of which turns the horizontal shaft W , hereinbefore referred to.

The rod L^4 passes through the band M^4 , fixed to one side of a slide-bar, N^4 , arranged to move or slide in the ends of standards O^4 , secured to one side of the bed-plate A .

From the lower side of the slide-bar N^4 extends a bent or curved arm, P^4 , which, by its straight portion O^4 , is secured in the slide-bar N^4 by means of nuts R^4 , so that it can be adjusted to project more or less by its curved end.

S^4 is an arm secured to horizontal crank-shaft W , and notched at T^4 , which arm, as the said shaft W revolves and rises in its elongated bearings, abuts against the downward-projecting lug U^4 of the slide-bar N^4 and carries such bar along with it, and through the connecting parts described slides the mold out from under the plunger, when, depressing the lever-handle A^2 , the said arm S^4 then acts upon the shoulder or corner V^4 of the curved arm P^4 , and again sliding the slide-bar, but in an opposite direction to that above explained, moves the mold under the plunger and in position for being operated upon by it.

The outward and inward movement of the mold above described is to be arranged so as to occur at the proper times with reference to the upward and downward movement of the plunger or follower.

To enable the handle or lever A^2 to be changed in position upon the shaft W , to which it is secured, I employ a ratchet-clutch, X^4 , as plainly shown in the several figures of the drawings, whereby, as is obvious, the desired result can be secured.

Having thus described my invention, I claim as new and desire to secure by Letters Patent—

1. The plunger or follower L , hung on a sliding head or frame moving upon guides E E , and connected, through rods U , with crank-arms of a shaft, W , arranged in slotted bearings, to the opposite ends of which crank-arms rods z are connected at one end, and at their other hung upon fixed pivots X , substantially as and for the purpose specified.

2. The mold B^4 , arranged and connected with the shaft for operating the plunger in such a manner as to be moved under and away from the line of movement of the plunger, substantially as and for the purpose described.

3. The head-plates M and R , rods O and Q , cross-bars P , springs R^2 , when all arranged and connected together and to the plunger so as to operate substantially as and for the purpose set forth.

The above specification of my invention signed by me this 30th day of April, 1866.

HIRAM DILLAWAY.
